UNITED STATES PATENT OFFICE.

WILLIAM M. DAINTREY, OF NEW YORK, N. Y.

DESIGN FOR CARPET.

SPECIFICATION forming part of Design No. 26,860, dated March 30, 1897.

Application filed February 15, 1897. Serial No. 623,575. Term of patent 31 years.

To all whom it may concern:

Be it known that I, WILLIAM MANSELL DAINTREY, a subject of the Queen of Great Britain, and a resident of the city, county, 5 and State of New York, have invented a new and original Design for Carpets and Borders, of which the following is a specification.

This invention comprises two parts, namely, the design A for a carpet and the design B 10 for a border; and I do hereby declare that the drawing accompanying this specification conveys to any one a clear understanding of the same and is sufficient to enable such person to use my invention.

15 The body A is characterized by a continuous pattern of small closely-associated figures of nondescript design.

The border B is characterized by an inner band of figures resembling figures of the

body, by two contiguous rows of leaf-like figures, and by large and small figures of nondescript design near the outer margin.

What I claim as new, and desire to secure by Design Letters Patent, is—

1. In the design for a carpet, the body A, 25 substantially as shown.
2. In the design for a carpet, the border B, substantially as shown.
3. The design for a carpet, consisting of the body A and the border B, substantially 30 as shown.

In testimony whereof I have signed my name to this specification in the presence of two subscribing witnesses.

W. M. DAINTREY.
